ATTORNEY

UNITED STATES PATENT OFFICE.

HERBERT E. BRIDGWATER, OF SYRACUSE, NEW YORK, ASSIGNOR TO REMINGTON TYPEWRITER COMPANY, OF ILLION, NEW YORK, A CORPORATION OF NEW YORK.

TYPEWRITING MACHINE.

Application filed July 31, 1924. Serial No. 729,225.

To all whom it may concern:

Be it known that I, HERBERT E. BRIDGWATER, citizen of the United States, and resident of Syracuse, in the county of Onondaga and State of New York, have invented 5 certain new and useful Improvements in Typewriting Machines, of which the following is a specification.

My invention relates to typewriting or 10 like machines, and more particularly to the paper feed mechanism thereof.

The main object of my invention, generally stated, is to provide improved means 15 for mounting the paper feed release lever or device in order to render the construction more substantial and provide for readily mounting, detaching and replacing such lever or device.

To the above and other ends which will 20 hereinafter appear, my invention consists in the features of construction, arrangements of parts, and combinations of devices set forth in the following description and particularly pointed out in the appended 25 claims.

In the accompanying drawing, wherein like reference characters indicate corresponding parts in the different views,

Figure 1 is a fragmentary fore-and-aft 30 vertical sectional view, with parts omitted, of a carriage equipped with the devices of my invention; the section being taken to the right of the line 1—1 in Figure 2 and looking in the direction of the arrow at 35 said line.

Figure 2 is a detail fragmentary rear elevation of the same showing the right-hand end portion of the carriage.

Figure 3 is a detail transverse sectional 40 view of the release lever mounting; the section being taken on the line 3—3 of Figure 1 and looking in the direction of the arrow at said line.

Figure 4 is a detail perspective view of 45 the bearing member; the support to which it is attached being shown in dot-and-dash lines.

Figure 5 is a detail perspective view of 50 the pivot on which the release lever is supported.

The various views show the parts on an enlarged scale for clearer illustration.

The present invention is in the nature of

an improvement of the constructions disclosed in the patent to Joseph B. Holden, 55 No. 1,458,133, dated June 12, 1923, and in an application of the said Joseph B. Holden filed July 1, 1924, Serial No. 723,489.

The invention is shown embodied in the present instance in a Remington portable 60 machine though the invention is not restricted to use in such machines, but may be included in typewriting or like machines generally. Only so much of the machine is shown as is necessary to arrive at an understanding of the present invention.

In the Remington portable machine many parts thereof are made of comparatively thin sheet metal to provide a light and compact machine. Heretofore in such machines 70 it has been customary to form as an integral part of a sheet metal support for the feed rollers a turned bearing member in which was firmly fixed and permanently secured a pivot pin on which the feed roller release 75 lever was pivoted, as disclosed in said Holden patent. Considerable strain is exerted on the parts to cast off the feed rollers, and in the prior construction injury sometimes resulted which rendered replacement 80 of certain individual parts necessary. In such prior construction replacement of individual parts was, to say the least, difficult and in some instances required more extensive replacements to attain the desired ends. 85 By my present construction a more substantial and effective mounting for the release lever is provided and one in which the necessity for individual replacement is less liable to occur, but which may nevertheless be 90 readily effected when desired, as will hereinafter clearly appear.

The main sheet metal body portion 1 of the carriage carries end plates 2 provided with bearings to support the spindle 3 of a 95 cylindrical platen 4. Paper feed rollers 5 are supported by a plurality of carriers 6, which in turn are mounted for a slight rocking motion on a supporting member 7, preferably made of sheet metal. This member 100 7 is formed with integral bearing portions 8 that receive pivot rods 9 supported by sheet metal brackets 10 detachably secured to the main body portion 1 of the carriage. The supporting member 7 extends throughout a 105 considerable portion of the length of the

carriage and is mounted as described to receive a fore and aft pivotal movement to press the feed rollers 5 against the platen, or the paper thereon, by a forward movement, and simultaneously release the feed rollers by a rearward pivotal movement. The feed rollers 5 are normally held against the platen by springs 11 which bear downwardly against arms 12 that are integral 10 with and project forwardly from the sheet metal support 7, as disclosed in said hereinbefore mentioned Holden application.

It has been found desirable to provide a substantially U-shaped channel iron 13 15 of sheet metal which constitutes a re-inforcing or stiffening strip that is fixedly secured to the support 7 and extends longitudinally thereof throughout its length. This strip stiffens the support 7 and causes the cast-off 20 motion transmitted to it at one end to effectively carry all the feed rollers away from the platen.

As thus far described in detail, the parts 25 may be constructed substantially as disclosed in either the said Holden patent or application; the parts in the present instance being like the corresponding parts disclosed in said application.

In order to cast off the feed rollers, I 30 provide a release lever 14 fulcrumed on the pivoted support 7 and adapted to coat at its lower free end portion with a roller contact 15. This roller is mounted on a pivot pin 16 carried by a bracket 17 adjustably 35 secured by screws 18 to the foot-piece 19 of the right-hand end plate 2 of the carriage.

The upper end of the release lever 14 is 40 provided with a finger-piece 20, whereas the lower end portion of the lever has two semi-circular notches 21 and 22 therein; each conforming to the curvature of the roller 15 with which it coats. When the parts are in the position shown in Fig. 1, 45 the feed rollers, omitted from this view to avoid confusion in the illustration, are in the normal position, spring pressed against the platen. When, however, the finger-piece 20 is shifted rearwardly from the Fig. 50 1 position, there is a wedging action of the lever against the contact roller 15 which carries the fulcrums of the lever rearwardly and with it the support 7 on which it is pivoted. This turns the support 7 rearwardly on its pivots 9 and carries the feed rollers away from the platen. An extreme 55 backward movement of the finger-piece 20 brings the recess 22 into register with the roller contact 15, and when the latter is seated in said recess the feed rollers will 60 be held against return movement from their cast-off position. Forward pressure exerted on the finger-piece 20 is effective to displace the lever from its cast-off position, 65 permitting the springs 11 to return the parts

to the Fig. 1 position and apply the force of the springs to the feed rollers.

Formerly the pivot by which the release lever was connected to and carried by sheet metal support 7 was permanently fixed in 70 an integral bent bearing ear formed on the member 7. This led to the difficulties hereinbefore pointed out and which are overcome by my present invention, as will now appear.

I provide by the present construction a substantial cast metal bearing member 23, shown in detail in Fig. 4. This bearing member has an open-mouth substantially U-shaped bearing opening 24 therein which 80 receives the pivot of the release lever, designated as a whole by the reference numeral 25 and shown in detail in Fig. 5. From a consideration of Figs. 1 and 4 it will be understood that when the bearing member 23 is secured against the rear face of the pivoted support 7 the latter closes the open mouth of the bearing opening 24 and prevents a removal of the pivot 25 from such opening. In order to firmly though detachably secure the bearing member to the support 7, I provide a transverse opening 26 through the bearing member and pass the stem of a headed screw 27 through such opening; the threaded end of the screw engaging in a tapped opening in the support 7 and its re-inforcing strip 13. The bearing member also has a flange 28 that overlies the upper edge of the support 7, as clearly shown in Fig. 4. 100 This prevents the bearing member from turning on the screw 27 and the latter holds the member firmly clamped against the rear face of the support.

It will be seen that the pivot 25 is formed 105 with two enlargements or shoulders 29 and 30 that embrace the bearing member on opposite sides and prevent an axial displacement of the pivot in its bearing opening 24. One of these heads 29 is slabbed off to provide a flat face 31 which, when the parts are in place, bears against the rear flat face of the support 7, as shown in Fig. 1, and prevents the pivot from turning in its bearing opening or seat 24.

Outside of the enlargement or shoulder 30 on the pivot is a slightly reduced bearing portion 32 on which the release lever 14 is mounted and adapted to turn. Beyond the portion 32 the pivot is reduced to provide a bearing portion 33 on which a spring plate 34 is mounted to turn. This plate extends upwardly beside the release lever and has its upper end bent laterally at 34a where it extends through an opening 35 in said lever and tends to prevent any undue looseness of the lever on its pivot. The portion 33 of the pivot also receives a washer or head 36 which is firmly held in place by riveting the outer end of 120 125 130

the pivot as indicated at 37. The release lever and plate 34 are thus held in place on the bearing portions 32 and 33 respectively of the pivot, being confined between 5 the enlargement 30 and the head 36.

The present construction provides a substantial and firm mounting for the release lever on the sheet metal support 7, and one which enables the lever to be readily mounted on the support. Nevertheless the lever, its pivot 25 and the plate 34 may be readily detached as a unit and replaced should occasion require; the lever and its connected parts being detachable from the bearing member when the latter is detached from the support 7.

What I claim as new and desire to secure by Letters Patent, is:—

1. In a typewriting or like machine, the combination of a feed roller support, a release lever therefor, and means for pivotally mounting the lever on said support comprising a bearing member detachably connected to said support, and a pivot on which 25 said lever turns and which is seated in and supported by said bearing member and detachable therefrom when the bearing member is detached from said support.

2. In a typewriting or like machine, the combination of a feed roller support, a release lever therefor, and means for pivotally mounting the lever on said support comprising a bearing member detachably connected to said support, and a pivot on which 35 said lever turns and which is seated in and supported by said bearing member and detachable therefrom when the bearing member is detached from said support, said pivot having a shoulder and a head, the latter being 40 riveted thereon and between which shoulder and head the lever is received and adapted to turn.

3. In a typewriting or like machine, the combination of a feed roller support, a release lever therefor, and means for pivotally mounting the lever on said support comprising a cast metal bearing member detachably connected to said support, and a pivot on which 45 said lever turns and which is seated in and supported by said bearing member and is detachable therefrom when the bearing member is detached from said support, said pivot coacting with the bearing member to prevent an axial movement 50 of the pivot relatively to said member.

4. In a typewriting or like machine, the combination of a pivoted feed roller support, a release lever for shifting said pivoted support, a contact with which said lever 55 coacts, and means for pivotally mounting the lever on said pivoted support comprising a bearing member detachably secured to said support and having a substantially U-shaped bearing opening therein, and a pivot 60 on which said lever turns and which is

seated in said bearing opening and supported by said bearing member and detachable therefrom when the bearing member is detached from said support.

5. In a typewriting or like machine, the combination of a feed roller support, a release lever therefor, and means for pivotally mounting the lever on said support comprising a bearing member detachably secured against a side and overlapping an 70 edge of said support and having an open-mouth bearing opening closed by the support when said member is in place, and a pivot on which said lever turns and which is seated in said open-mouth bearing and is 75 removable therefrom when the bearing member is detached from said support.

6. In a typewriting or like machine, the combination of a feed roller support, a release lever therefor, and means for pivotally mounting the lever on said support comprising a cast metal bearing member detachably secured to said support, and a pivot on which 80 said lever turns, said pivot being detachably seated in a bearing opening in said bearing member and having enlarged portions that embrace the bearing member on opposite sides thereof and prevent an axial movement of the pivot.

7. In a typewriting or like machine, the combination of a feed roller support, a release lever therefor, and means for pivotally mounting the lever on said support comprising a cast metal bearing member having an open-mouth bearing opening 90 therein that is closed by said support when the bearing member is secured thereto, a screw for detachably securing said member to the support, and a pivot on which said lever turns, said pivot being seated in said open-mouth bearing opening and detachable 95 therefrom when the member is detached from said support and having enlarged portions that embrace the bearing member on opposite sides thereof and prevent an axial movement of the pivot, said pivot also having a head riveted on one end thereof and between which head and one of said enlarged portions said lever is confined and adapted 100 to turn.

8. In a typewriting or like machine, the combination of a feed roller support, a release lever therefor, and means for pivotally mounting the lever on said support comprising a cast metal bearing member having an open-mouth bearing opening therein 110 that is closed by said support when the bearing member is secured thereto, and also having a flange that engages over one edge of the support for preventing said member from turning thereon, a screw for detachably securing said bearing member to said support, and a pivot on which said lever turns and which is held in place in said open-mouth bearing opening when said 115 120 125 130

member is secured to the support but may be removed from such opening when the member is detached from the support.

9. In a typewriting or like machine, the combination of a feed roller support, a release lever therefor, and means for pivotally mounting the lever on said support comprising a bearing member having an open-mouth bearing opening that is closed by said support when the bearing member is secured thereto, a screw for detachably securing said bearing member to the support, and a pivot on which said lever is mounted to turn, said pivot being seated in

said bearing opening and having enlarged portions that embrace the bearing member and prevent an axial movement of the pivot, one of said enlarged portions having a flat face to coact with the support and prevent the pivot from turning in its bearing opening.

Signed at Syracuse, in the county of Onondaga, and State of New York this 26th day of July A. D. 1924.

HERBERT E. BRIDGWATER.
